United States Patent Office

Des. 212,057
Patented Aug. 20, 1968

212,057

TYPEWRITER

Frank C. Fusco, Monroe, Norman C. Gold, New York,
and William Gold, Great Neck, N.Y., assignors to Louis
Marx & Co., Inc., New York, N.Y., a corporation of
New York

Filed July 26, 1966, Ser. No. 3,905

Term of patent 14 years

(Cl. D64—11)

FIG. 1 is a front, left side and top perspective view of a typewriter embodying our new design; and

FIG. 2 is a rear, right side and top perspective view thereof.

The dominant features of the design reside in the portions shown in full lines conventional mechanical details being shown in broken lines.

We claim:

The ornamental design for a typewriter, as shown and described.
